UNITED STATES PATENT OFFICE.

LLOYD R. SMITH, OF MILWAUKEE, WISCONSIN.

PROCESS OF MAKING INTEGRAL CROSS-BAR BLANKS FOR VEHICLE-FRAMES.

1,323,555.

Specification of Letters Patent.

Patented Dec. 2, 1919.

Application filed April 11, 1919. Serial No. 289,187.

To all whom it may concern:

Be it known that I, LLOYD RAYMOND SMITH, a citizen of the United States, residing in Milwaukee, in the county of Milwaukee and State of Wisconsin, have invented a certain new and useful Improvement in Processes of Making Integral Cross-Bar Blanks for Vehicle-Frames, and do hereby declare that the following is a full, clear, and exact description thereof, such as will enable persons skilled in the art to which the invention pertains to make, use, and practice the same, reference being had to the drawings hereto attached for disclosure as to certain details of construction by which my process may be carried out.

My invention relates to an electric welding process and is used in the production of sheet metal blanks from which the cross bars and other flanged or channeled bars of automobile frames are made.

In many types of automobile frames, the contour of the blanks from which the cross bars are formed is of such varying and irregular outline that an excessive amount of material is required for the production of such blanks. In other words, the rectangular area indicated by the extreme dimensions of the contoured blank exceeds the superficial area of such blank by as much as one hundred per cent. in some instances.

The amount of waste material or scrap following inevitably the operation of punching contoured blanks from metal plates or sheets, is, therefore, disproportionately large, when compared with the results attained. This waste of material is directly due to the presence of gusset projections extending from the body of the blank in the plane of the latter, and at one or more sides thereof. On account of the limited uses for the scrap which results from the punching of complete cross bar blanks from metal plates or sheets, the cost of the production of such blanks is rendered excessive, inasmuch as the greater part of the waste material must be disposed of as scrap.

The blanks are converted into channeled cross bars by bending the marginal portions at a right angle to the web, this drawing operation leaving the gusset projections in the plane of that marginal portion of which they are a part. In such position, the gussets act as braces or stays when the parts of the automobile frame are assembled and secured together.

My invention comprises the formation of what may be designated the body blank, it having greater regularity of outline by reason of the omission of the gusset projections in the production of such blank. The gusset projections are separately formed and are arranged in proper relation to the body blank, the body blank and the gusset projections being placed in the same plane, with the edges of the parts in proximity at the points where they are to be joined. A welding current is then applied to the parts to effect their fusion and union. A cross bar blank so constructed lacks none of the elements of the rigidity and strength required in its uses.

By producing the body blank without the gusset projections, the dimensions of the blank in the direction of its width are greatly reduced, and the number of such blanks which may be punched from a metal plate or sheet is largely increased. The gusset projections may be produced from the scrap of the plate or sheet after the body blanks have been punched therefrom. These operations result in the practically complete utilization of the whole of the metal plate or sheet, so that the waste is reduced to a minimum.

In the accompanying drawings, I have shown a common form of cross bar blank, the showing being merely conventional, to enable a ready comparison to be made between the old method and my new method of producing blanks.

In the drawings,

Fig. 1, shows the skeleton of a metal sheet or plate of given dimensions, the cross bar blanks having been punched therefrom, and indicating the excessive amount of scrap remaining, according to the old method of manufacture.

Fig. 2, is a similar view showing the increased number of blanks produced and the lessened amount of scrap remaining in the plate, resulting from the use of my invention.

Fig. 3 is a view of a cross bar blank constituted of a body portion with the gusset projections welded thereto in accordance with my improvement.

Figs. 4 and 5, are fragmentary views showing modifications of the arrangement of the gusset projections with relation to the body blank.

Referring to the drawings, A, Fig. 1, indi-

cates a metal sheet or plate from which cross bar blanks of approved contour have been punched. It will be observed that the formation of the gusset projections as integral parts of the blank necessitates a wide separation of the blanks along the central line of the plate, with the result that pieces of waste material or scrap, *a*, of large proportions in the areas alternating with those from which the blanks are punched, are produced, and that such waste production is unavoidable.

In Fig. 2, B, indicates a metal plate or sheet of the dimensions of the plate A, in Fig. 1. In connection with this view, it will be seen that an increased number of cross bar blanks, but formed without the gusset projections, has been punched therefrom, and that the area of the waste or scrap, *b*, in the spaces intermediate the punchings is largely reduced. This will be apparent from a comparison of the two figures.

Specifically stated, the maximum number of blanks of the contour shown which can be punched from the metal plate in Fig. 1, is four, while the number of such blanks with the same general outlines which can be punched from the metal plate in Fig. 2, the dimensions of the sheet in each case being the same, is seven, an increase of seventy five per cent. in the productive output. At the same time, as hereinbefore indicated, the waste or scrap is reduced to a minimum.

In Fig. 3, I have indicated one of the cross bar body blanks by the letter C, and the separately formed gusset projections by D and D'. A blank C and two gussets D and D', will be assembled in the same plane, with their edges at the points of union in proximity to each other, such points being indicated *d* and *d'*. When so assembled an electrical welding current will be applied and the parts will be heated to a fusion at their meeting edges and thus joined together.

In Fig. 4, I have shown a modified manner of attaching the gusset D², to the body blank. In this figure, the parts are interlocked, as at *d*², in addition to the welding operation. In Fig. 5, the welding line *d*³ between the body blank and the gusset D³, is at an angle from that shown in Fig. 3. It is within the scope of my invention to arrange the welding line at any desired angle, and the latter may be varied to meet the exigencies existing in any particular type of cross bar blank. The dotted lines in Fig. 3, indicate the lines upon which the margins of the blank are to be folded in forming the channeled cross bar. The folding line will not ordinarily be coincident with the welding line, but the folding line may cross the welding line, if desired.

The body blank and the gussets which are

to be welded thereto are held in their proper relative positions in a jig or carrier, by means of which they are presented to the welding devices, which latter may be of any approved construction.

In carrying out the operation of welding the gussets to the body blank, I prefer to use a fusible metallic electrode, which while forming one terminal of an electric circuit, will deposit a quantity of fused metal in the joint, to thus insure a more perfect union of the parts. The work to be welded will form the other terminal of the circuit. My invention, however, contemplates the use of a carbon pencil or disk electrode, or any form of electrode which will produce the desired heat at the welding line.

What I claim and desire to secure by Letters Patent, is:

1. The method of manufacturing integral vehicle frame cross bar blanks from sheet metal with minimum waste of material, which consists in cutting a sheet metal strip to form a series of gussetless and closely located body blanks along contour lines which coincide in the strip as to the side margins of successive blanks, separately cutting gusset flanges, and subsequently integrally uniting the gusset flanges to the body blanks by placing them edge to edge in the same plane, and electrically welding them together.

2. The method of forming integral cross bar blanks for automobile frames with minimum waste of material, which consists in cutting a piece of sheet metal along lines which destroy the integrity of the blank, while permitting the severance of closely located gussetless members along coinciding contour lines, separately cutting the gusset members and subsequently uniting the body and gusset members of each individual cross bar by placing them edge to edge in the same plane, and restoring the integrity of the blank by electrically welding the members together.

3. The method of manufacturing integral cross bar blanks for vehicle frames, which consists in cutting from a sheet of metal a succession of closely located and gussetless body blanks along coinciding contour lines with interlocking provisions for the gussets, separately cutting gusset members with corresponding interlocking provisions, assembling the said elements in the same plane in interlocked relation, and uniting the said elements by welding at the line of assembly.

In testimony whereof, I have signed my name at Milwaukee, Wisconsin, this 5th day of April, 1919.

L. R. SMITH.
